UNITED STATES PATENT OFFICE

SAMUEL B. KRAUT, OF SOUTH BEND, INDIANA, ASSIGNOR TO WESTINGHOUSE ELECTRIC & MANUFACTURING COMPANY, A CORPORATION OF PENNSYLVANIA

CABLE TERMINAL

Application filed February 4, 1928. Serial No. 251,854.

My invention relates to cable terminal junction boxes and has particular relation to a quick-disconnecting cable terminal known as a "pothead", particularly suitable for 5 high-tension circuits.

In high-tension circuits, such as those used in street lighting, a cable terminal is necessary at the point where the cables enter the lighting standards. These cable terminals 10 must be so constructed that the conductors leading inside the standard to the lighting unit may be disconnected from the circuit in case the lighting standard is thrown down, in order that dangerous high-tension currents 15 shall not be present in the lighting unit.

Most of the lighting circuits are of the series type so that, if one lighting unit is disconnected, the other lighting units in series with it will be extinguished. Therefore, it 20 is desirable to provide means such that, when one lighting unit is disconnected, an automatic cutout is brought into operation and the lighting current shunted through this connection to keep the remaining units 25 burning.

An object of my invention is to provide a quick-disconnecting cable terminal or pothead which is watertight and does not need to be sealed in with sealing compound.

Another object of my invention is to provide 20 a cable terminal in which the terminal connections need not be soldered to the cable wire.

Another object of my invention is to provide 35 a cable-terminal support or bracket which is adapted to ground the cable sheaths commonly used in cable work of this character and which may be adjusted to accommodate different cable lengths so that the cables 40 need not be accurately cut to proper length.

Other advantages of my invention will become apparent from the following description when taken in connection with the accompanying drawings, in which

Figure 1 is a sectional view of the cable terminal showing the cable ends electrically connected through the cable terminal.

Fig. 2 is a side elevational view showing 50 the cable terminal and a supporting bracket,

Fig. 3 is a front elevational view of the cable terminal and bracket shown in Fig 2, and

Fig. 4 is an enlarged sectional view of a conductor with which my device may be utilized.

Referring to the drawings, a preferred 55 form of my device comprises a base or lower member 1 and a cap or top member 2 of insulating material, such as porcelain, phenolic condensation product or the like. The lower 60 member comprises a body portion 3 having a recess 4 at its upper inner part. The body portion is oval in cross-section and is provided with two channels 5 and 9 extending from the lower outside wall into the recess 4. In order 65 to facilitate insulation of the conductors, depending circular flanges 6 are provided. The channels 5 and 9 are constricted at their upper portions by a flange portion 7 which is adapted to permit the insertion of metallic 70 bushings 8 therein. The bushings are placed in the constricted portions of the channels 5 and 9 and are then fastened in place by screwing down nuts 11.

The bushings 8 insure good electrical connection 75 between the cable conductors and metallic connection strips 13, 14 and 34 and 35 and also minimize the possibility of breakage at the constricted portions of the channels 5 and 9.

In my preferred construction, a recess 12 is provided between the channels 5 and 9, and metallic strips 13 and 14, extending down into this recess, are electrically connected to, and fastened by, the bushings 8 and nuts 11. 80 The strips 13 and 14 are provided with crimped portions 15 near their lower ends. Strips 16, of resilient material, act as springs for pressing the contact strips 13 and 14 toward each other.

The top member 2 is provided with a depending flange 21 which is adapted to fit down over the body member 1 to prevent water from draining from the sides of the top member and into the recess between the 85 top and bottom members.

The top member is also provided with a recess 23 corresponding to the recess 4 in the lower member and cooperating therewith to constitute a chamber 22. The top member 100

is also provided with channels 24 and 25 which communicate with the recess 23 to permit entrance of the cable ends 26 and 27. The channels 24 and 25 of the top member 5 are provided with constricted portions 28 and 29 in which bushings 31 are inserted, in the same manner as are the bushings 8 in the bottom member.

Two downwardly extending metallic strips 34 and 35 make electrical connection with, and are fastened by, the bushings 31 and nuts 11. The strips 34 and 35 are provided with crimped portions 36 which coact with the crimped portions 15 of the lower 15 contact strips to hold and lock the cap 2 in place on the base.

Insulating strips 37 are fastened under the top metallic strips 34 and 35 to prevent them from making electrical contact with each other. The insulating strips may be removed and a film cutout placed between the metallic strips 34 and 35 to provide a protective device, if desired.

Tubular end pieces 38 have screw threaded 25 extensions that project through the bushings 8 and 31 to receive clamping nuts 72 and are provided with two set screws 41 and 42 to clamp the terminals of cable conductors 26 and 27 and 43 and 44 between them and the inner walls of the end pieces. It will be noted that the set screws are in a staggered relation, such that the cable conductor ends are crimped and thus held tightly in position.

35 A soft-rubber washer 32 is located between the junction of the top and bottom members in order that the recess 23 may be sealed against moisture. In order to seal the various recesses against the entrance of moisture, bell-shaped caps 47 of insulating material 40 may be fitted over the flanges of the top and bottom members to engage the cables or the flanges and cables may be taped.

The cable terminal may be fastened inside of a lighting standard by means of a bracket 49 (Figs. 2 and 3). The bracket comprises an L-shaped member 50 provided at its lower extremity 51 with openings 52 so that the bracket may be bolted to a suitable base 53 inside the lighting standard or set in the concrete which constitutes the base upon which the standard is mounted. The upper portion of the bracket comprises a member 54, bent to facilitate taping of the cables and having a U-shaped member 55 adapted to fit the body member 1 of the cable terminal. Another U-shaped member 56 is adapted to engage the lower cable conductors 43 and 44 and to be clamped to the supporting bracket by means of a bolt 57.

The upper and lower portions 54 and 50, respectively, of the supporting bracket are provided with slots 58 and a clamping means 59 so that the upper member may be adjusted vertically to raise or lower the cable termi-

nals to compensate for any deficiencies in length.

The high-tension cables now in use usually comprise a conductor 60, an insulating layer 61, a metallic sheath 62 of lead or the like, another insulating layer 63, a metallic, spirally wrapped outer sheath 64 and an insulating and an abrasion resisting covering 65 (Fig. 4). It is desirable that the metallic sheaths be grounded in order to prevent the setting up of electrical charges in the cable sheaths.

Therefore, I have provided a clamp 66 adapted to make connection with the metallic sheaths 62 and 64 and to ground them through the supporting bracket to any suitable grounding connection (not shown). The clamp is provided with two finger portions 67 and 68 adapted to grip the inner sheath and two other finger portions 69 and 70 adapted to grip the outer sheath. In this way, the metallic sheaths are grounded and the cable terminals are relieved of the strain incident to support of the supply cables.

In installing the cable terminal, the lower portion of the bracket is fastened to any suitable support inside of the lighting standard, and the upper portion of the bracket is adjusted to its highest point. The cable ends are then cut off to proper length and the insulation stripped for a space to bare the conductors. In order to provide contact with the grounding clamp, the supply cable is stripped of insulation to the inner sheath at a point 71 just below the cable terminal and to the outer sheath just below this point. The connector tubes are then fastened to the cable wires by the set screws. The body member 1 of the cable terminal is then put into place, and the lugs 38 fastened inside the bushings by means of nuts 72.

The upper portion 2 of the cable terminal is then connected to the secondary cables 26 and 27 in the same manner, and the supporting brackets and clamps are screwed down into proper engagement.

Referring to Fig. 1, in operation, when the cap is put into place, the upper contacting strips force the lower contacting strips apart, and electrical connection is made between the lower contact strips and the corresponding upper contact strips, so that electrical connection is completed between cables 43 and 26 and between cables 44 and 27. If, for any reason, the lighting standard is thrown down or injured, the cap is pulled away from the base member, thus disconnecting the branch-circuit conductors from the supply circuit. The lower contact strips then spring together, thus completing an electrical connection with the other lighting units of the series circuit.

My device does not need to have the cables sealed in with sealing compound, as has been customary in the past, since adequate protection of the exposed parts from water is pro-

vided. There are no openings in the cap except the protected channels 24 and 25 and it is, therefore, watertight.

It is not necessary that the cable wires be soldered in place in the tubular connectors, and vertical adjustment of the cable terminal is provided in order to allow for any error in cutting off the cable leads. The cable top may be readily removed by a vertical pull but is not readily removable by a side pull, thus preventing accidental loosening of the top from the body member.

Although I have described a specific form of my device, I do not wish to be limited thereto, since modifications may be made by those skilled in the art without departing from the spirit and scope of my invention, as defined in the appended claims.

I claim as my invention:

- 20 1. A quick-disconnecting cable terminal comprising a top member and a bottom member, said top member having a depending flange adapted to fit down over said bottom member, the top member having a recessed inner portion and a plurality of channels communicating with said recess, bushings disposed in said channels, connectors extending through said bushings, the bottom member having an inner recessed portion and a plurality of openings communicating therewith, bushings disposed in said openings, and connectors extending through said bushings and coacting contact members disposed in said recesses.
- 25 2. A quick-disconnecting cable terminal comprising a top member and a bottom member, said top member being disposed to fit down over said bottom member, said top member and said bottom member being disposed to provide a recess between them and also being disposed to provide a plurality of openings communicating between the recess and the outer walls of the top and bottom members, bushings disposed in said openings, 40 coacting contact members fastened to said bushings and connectors extending through the bushings to make electrical connection with the coacting contact members.
- 30 3. A quick-disconnecting cable terminal comprising a top and a bottom member, said top and bottom members severally comprising a body portion having a recess intermediate its ends and disposed to provide openings leading from the outside wall to said recess, bushings disposed in said openings, and connectors extending through said bushings and electrically connected thereto, a sealing ring disposed at the junction of the two members, and coacting contacts disposed in 45 said recesses.

In testimony whereof, I have hereunto subscribed my name this 26th day of January 1928.

SAMUEL B. KRAUT.
